UNITED STATES PATENT OFFICE

CHESTER A. SCOTT, OF FORT WAYNE, INDIANA, ASSIGNOR TO DEISTER CONCENTRATOR COMPANY, OF FORT WAYNE, INDIANA, A CORPORATION OF INDIANA

SCREEN FOR GRANULAR MATERIALS

Application filed April 28, 1926. Serial No. 105,111.

My invention relates to screens for granular materials and more particularly to means for sustaining the screen wire cloth when under tension ready for use.

Heretofore very efficient screens have been constructed with a binding strip at each longitudinal end of the screening medium which is free at the sides and is secured to the frame at the ends and vibrated by blows transmitted from above to a rigid cross member secured to the under side of the screening medium. Where the screening medium was bent sharply to attach it rigidly to the frame, particularly at the lower end, the constant vibration of the screen caused its longitudinal wires to crystallize and break.

The principal object of my invention is to provide a flexible connection at the longitudinal ends of the screening medium which is free at the sides, so that these suspension bar end connections at the bottom, and similarly functioning connections at the top, will rock in relation to the frame, so as to adjust the position of these bound ends to meet each on-coming wave of the screening medium. This ensures vibration of the entire length of screening medium, increasing the efficiency of the screen and practically eliminating the tendency of the longitudinal wires to crystallize along the line where they are secured at the ends.

The particular embodiment of my invention selected for illustration is with my improvements added to a screen of the type shown in Letters Patent No. 1,456,067, issued to Richard A. Leahy May 22nd 1923.

Figure 1 is a top plan view of such a screening apparatus;

Fig. 2 is a side elevation of the same with parts of the supporting structure broken away, and a part of the side frame broken away at the delivery end to show the sustaining means;

Fig. 3, an enlarged detail, is of a portion of one side of the frame at the delivery end, showing the means of flexibly holding the screening medium in tension at the delivery end by the knife blade support of the suspension bar;

Fig. 4, an enlarged detail, is a section on the line 4—4 of Fig. 1, and

Fig. 5, an enlarged detail, is a view of one corner of the frame at the delivery end showing the screening medium held between a binding bar and the suspension bar.

Referring now to the drawings, a suitable supporting structure S is provided, and on this is mounted a screen frame F pivoted at its lower end at f and provided at its upper end with simple, quickly adjusted tilting mechanism, consisting of a bar T with a gear-rack t^1 on one edge, whose teeth are adapted to be engaged by the teeth of the pinion t^2 fixed to the shaft t^3 and adapted to be rotated by the pilot wheel t^4 to raise or lower the upper end of the screen frame. On its opposite edge the bar T is provided with ratchet teeth t^5 adapted to be engaged by the pawl t^6 , so that the upper end of the screen will be held in any position to which it has been adjusted, until the pawl is thrown back out of engaging position with the ratchet teeth by means of the handle t^7 . The inclination of the screen is adjusted from time to time as required to most efficiently and rapidly screen the granular material fed upon it.

The screen frame F is formed of any material suitable for building a rigid structure capable of carrying the weight and bearing the strain, such as I-beams, channel irons, and angle bars bolted or riveted together.

The flexible screening medium A may be of any desired mesh ranging from that of very fine mesh to that which is very large. The screening medium is finished at the upper longitudinal end by being clamped tightly by bolts a^8 or otherwise between bars a^1 , a^2 , faced with packing strips a^3 , a^4 respectively of rubber or other compressible material.

The suspension bar so formed has a U-shaped strap a^5 toward each end pierced by the shank of a bolt B whose cylindrical head b rests in the U-strap in such a manner as to permit considerable freedom in up and down vibration of the screen A. The bolt B passes through the upper end of the frame F and a bearing member b^2 whose horizontally placed

knife edge bearing surface b^3 bears upon the frame and is seated in a notch f^1 in the frame member in such a manner as to add considerable additional freedom of vertical vibration to the screening medium when the nut b^4 is suitably tightened down.

At its lower or discharge end the screening medium is clamped tightly by bolts a^7 or otherwise between a binding bar a^8 and the suspension bar a^9 faced with similar packing strips a^3 , a^4 respectively.

The suspension bar a^9 extends outwardly at each end beyond the edge of the screening medium to form a bearing a^{10} , having a knife edge bearing surface a^{11} adapted to oscillate in a V-shaped seat f^3 in a bearing block f^2 secured to the channel iron forming the side of the frame F by bolts f^4 or in any other suitable manner, thus providing for an up and down rocking motion of the screen at the discharge end. This flexible suspension of the screening medium allows it to vibrate throughout its length.

A bridge member D supports the vibration mechanism d operated by motor d^1 or otherwise and acting upon the screening medium through the tappet rod a^{12} .

It will be noted that this invention provides a screening apparatus of greatly improved screening efficiency. The screening medium is tensioned in an endwise direction and at each anchorage there is a knife edge pivot so constructed that the screening medium may vibrate freely between its points of suspension. The upper pivots are positioned beyond the upper end of the screening medium so that the pivot point at this end is beyond the end of the screen and accordingly there will be no dead point at that end but the screen will have a vibratory motion clear to the top. The lower end of the screen cloth passes over the edge of a bar which has its pivots laterally beyond the side edges of the screen. Accordingly, as the screen cloth is caused to vibrate at its medial portion, the waves of motion may travel clear to the lower end thereof. This means that there will be no blind or dead points anywhere on the screen and that even at the lower end thereof, the material will be kept in agitation until it passes off the end of the screen. Placing the pivot points laterally outside of the edges of the screen cloth renders this end of the screen entirely free of obstruction.

Obviously many changes may be made in the apparatus without departing from the spirit of my invention and I claim as within the scope of my invention all forms readable on the claim.

I claim as my invention and desire to secure by Letters Patent of the United States:—

In combination with an apparatus for screening granular material, having an in-

clined frame and a strip of resilient screening medium maintained under tension from the top and bottom edges in said frame, binding means for the bottom tension edge of said medium, a part of said binding means extended beyond the edge of said medium and provided with a knife-edge bearing adapted to co-act with said frame to form a flexible connection therewith, so that said vibration affect said end as well as the main body of the surface of said screening medium and permit the binding means to adjust itself to meet oncoming transverse waves of the screening medium, said connections being to the side of the frame at the delivery end, and said bottom edge binding means being free of other connections to the frame.

In testimony whereof I have hereunto set my hand.
